CLAIM

We claim the ornamental design for a battery receptacle, as shown and described.

DESCRIPTION

FIG. 1 is a front-left perspective view from above of the battery receptacle;

FIG. 2 is a detail view of a portion of the battery receptacle thereof;

FIG. 3 is a front-right perspective view thereof;

FIG. 4 is a detail view of a portion of a battery receptacle in FIG. 3;

FIG. 5 is a left side view of the battery receptacle in FIG. 1;

FIG. 6 is a right side view thereof;

FIG. 7 is a rear side view thereof;

FIG. 8 is a front view thereof;

FIG. 9 is a detail view of a portion of the battery receptacle in FIG. 8;

FIG. 10 is a top view of the battery receptacle in FIG. 1; and, FIG. 11 is a detail view of a portion of the battery receptacle in FIG. 10.

The broken lines shown in the drawings are included for the purpose of illustrating portions of the battery receptacle that form no part of the claimed design.
